UNITED STATES PATENT OFFICE.

MICHAEL J. OWENS, OF TOLEDO, OHIO, ASSIGNOR TO THE TOLEDO GLASS COMPANY, OF TOLEDO, OHIO, A CORPORATION OF OHIO.

GLASS-SHAPING MACHINE.

1,245,262.

Specification of Letters Patent.

Patented Nov. 6, 1917.

Application filed July 16, 1912. Serial No. 709,625.

To all whom it may concern:

Be it known that I, MICHAEL J. OWENS, a citizen of the United States of America, residing in the city of Toledo and county 5 of Lucas, State of Ohio, have invented certain new and useful Improvements in Glass-Shaping Machines, of which the following is a specification, reference being had thereto in the accompanying drawings.

10 The invention consists in a machine for shaping glass, comprising mechanism for making a blank and a transfer-device for taking the glass blank and transferring it, as, for instance, in the machine here illustrated, to a blowing-mold in which it may be blown to finished form; and further, in the construction, arrangement and combination of the blank-forming, transfer and blowing devices, as more fully hereinafter 15 described and pointed out in the claims.

I have here illustrated a traveling blank-forming mechanism of the type in which the blank is gathered into the blank-mold from the tank of molten metal, this mechanism being of the kind shown in the Bock Patent No. 870,664, dated November 12th, 1907, and a traveling blowing-mold arranged 25 beside the blank-forming mechanism with a transfer-device to move the blank from one 30 to the other.

In the drawings:

Figure 1 is a diagram plan of the blank-forming and blowing mechanism, showing the transfer mechanism in plan on the rotary table of the blowing mechanism;

Fig. 2 is a side elevation of a portion of the blank-forming mechanism, showing one mold in the gathering position and another mold having its lower or body portion open, 40 leaving the blank suspended by the neck ready for the transfer mechanism to engage it;

Fig. 3 is a side elevation of a portion of the blowing-mold, in position to receive the 45 blank; and

Figs. 4, 5 and 6 are side elevations of the blowing-table beside the mold, partly in section, showing the transfer mechanism in different positions during the transfer operation.

I do not deem it necessary to explain in detail the construction of the gathering blank-forming machine, as that is of the type of what is known as the Owens ma-

chine, and of the kind shown in the Bock 55 patent above referred to.

In short, this machine comprises a base 1 on wheels 2, supporting a central post or pillar (not shown) on which rotates the frame 3. This frame carries a series of 60 mold-arms 4 on each of which is supported a blank-mold. This blank-mold is made in two portions, the upper portion 5 called the neck-mold, made in separable halves carried on hinged arms 6 and automatically opened 65 and closed as the frame rotates, and the lower or body portion 7, made in separable halves carried on the hinged arms 8, which are likewise automatically operated by suitable cams (not shown) for opening and 70 closing the same during the travel of the frame.

The tank of molten glass is shown at 9, and during the rotation of the frame each mold is caused to lower at the tank to cause 75 its lower, open end to touch the glass, at which moment the air is exhausted from the mold, which causes the mold to be filled with glass and the blank formed. At the upper end of the mold a pin 10 projects into the 80 neck-mold to form an initial blow-opening and more perfectly form the neck of the blank, especially if a bottle is to be blown.

In the rotation of the frame and the blank-forming mechanism the lower edge of 85 the mold is dipped to the glass and the glass forced into the mold to form the blank, a cut-off (not shown) severs the string of glass from the bottom of the blank-mold, and the blank-mold is moved away from the 90 molten glass tank. As the mold travels away from the tank the sections of the body blank-mold are opened by a suitable cam mechanism to the position shown at the left-hand of Fig. 2, leaving the blank 12 suspended from the neck-mold. Mechanism is provided in the further travel of the blank-mold for opening the neck-mold sections to release the blank. Mechanism is also provided for closing the sections of 100 the body blank-mold and the neck-mold, and for raising and lowering the plunger 10; these operations being carried on by suitable cams and operating connections which are well-known and which are illustrated in the 105 Bock patent herein referred to.

Adjacent to this blank-forming mechanism is a blowing machine or blowing mech-

anism. This machine may be on the same frame or carriage (1) with the blank-forming mechanism or it may be on a separate carriage. I have shown it on a separate carriage 15, having suitable wheels so that the two machines may be moved side-by-side as shown in diagram in Fig. 1.

This blowing mechanism as here shown comprises a standard 16 upon which there is a rotating frame 17, on which are a series of blow-molds 18 made in sections, which sections are adapted to be opened and closed through the connections 19 which are operated by a roller 20 engaging with a cam 21 on a stationary pillar 21^a. On the same pillar at the top are arms 22 which guide the blow-heads 23, actuated by a lever 24, which lever has a crank-arm 25 having a roller 26 engaging a cam-way 27 secured to the pillar 21^a. The cam is of such construction that the blow-head is raised and lowered to and from the blow-mold in the well-known way. The blow-head is connected with a source of air under pressure through the pipe 28. 25 The blank-forming and blowing mechanisms being arranged side-by-side and traveling as shown by the arrows in Fig. 1, in order to transfer the blank from the blank-forming mechanism I employ the following apparatus: Secured on the traveling frame, or table 17, is a slide 30 working in radial guides 31 and having a roller 32 at its inner end engaging a cam-way 33, which cam-way is secured to the pillar 21^a and is shaped to 30 move the slide 30 in and out. The slide is provided on one face with the rack 34 which meshes with the gear-wheel 35, which gear-wheel is journaled at its lower end in the bracket 36 working in vertical guides 37 depending from the under-side of the table. The bracket is provided with an inwardly-extending arm 38 having a roller 39 engaging a cam-way 40 secured to the central pillar or pedestal below the rotating table 40 or frame, this cam being of such shape as to raise and lower the bracket 36 and with it the gear-wheel 35, at the proper time to carry out the functions hereinafter described.

50 The gear-wheel 35 passes through and is guided by a sleeve 41 which is secured to the edge of the rotating table 17 near the blow-mold. At the upper end of the gear-wheel 35 is attached a transfer-arm 42, in 55 the manner of attaching a crank-shaft. This transfer-arm at its outer end is provided with a forked blank support 44.

In arranging the blank-forming and blowing machines adjacent each other the blank-forming machine is arranged so that its molds travel on a higher level than those of the blow-mold, the difference in elevation of the two being shown in Fig. 4, where the blank is shown as being transferred from the 60 blank-mold and arranged at about the level

of the blank-mold, to a position above the blow-mold. The parts being thus constructed they operate as follows:

The blank-forming mechanism will gather the glass and form a blank, in the well-known manner, during the rotation of the frame of that mechanism, and then during the travel of the frame from the tank where the glass is gathered the lower portion, or body blank-mold, will open, as shown at the 70 left-hand of Figs. 1 and 2, leaving the blank suspended from the neck-mold. At this point in the operation the blank-mold most nearly approximates the blowing-mechanism, and the gear-wheel 35, through 75 the cam 40, will hold the transfer-arm 42 on a level with a point just below the bottom face of the neck-mold. The slide 30, by its cam 33, is drawn inward at this point, rotating the gear 35 and swinging the transfer-arm around, so that the supporting fork will embrace the blank just below the neck-mold (as shown in Fig. 1). As soon as this happens the neck-mold will be opened and will drop the blank from the neck-mold to rest 80 upon the fork, the blank being provided with an enlarged head 50 which supports it in the neck-mold and which will support it as it drops a short distance onto the forked support of the transfer-arm. As soon as this 85 happens the slide 30 is pushed outward, by the cam, which rocks the transfer-arm from the position shown in Fig. 1 to the position shown over the blow-mold. When the blank reaches the position over the blow-mold the 90 cam 40 will lower the gear 35 and its supported transfer-arm 42—and with it the blank—into the blow-mold, as shown in Fig. 5. Then the further outward movement of the slide 30 will disengage the transfer-arm 95 from the blank and allow it to drop into the blow-mold with its upper end, or head, resting upon the upper edge of the mold, and will also withdraw the transfer-arm to a position laterally beyond the blow-mold, as 100 shown in Fig. 1.

When the blank has thus been transferred to the blow-mold, the cam 27, operating the lever 24, will lower the blow-head upon the blow-mold and, air being admitted (which is 115 usually done by the lowering operation of the blow-head), will blow the blank to completed form in the blow-mold.

At a suitable point in the rotation of the table or frame 17 the blow-head will be 120 raised (and the air shut off) and the mold opened, so that the blown article may be removed therefrom; the blow-mold closing before it again returns to position to receive a blank from the blank-forming mechanism.

The mechanism described is especially desirable for the manufacture of very large ware—such, for instance, as three or five gallon glass bottles or receptacles or other similar glass-ware.

So far as I am aware I am the first to devise an apparatus in which a blank is formed combined with a blowing mechanism and a transfer mechanism which engages and removes the blank from the blank-forming mechanism to the blowing-mechanism. While I have shown and described an apparatus in which the blank is brought above and lowered into the blow-mold, it is obvious that the blank may be moved into the blow-mold while open and the blow-mold thereafter closed, but this is a mere matter of timing the cams for opening and closing the blow-mold in relation to the feeding movement of the blank thereto.

What I claim as new is:

1. The combination in a glass-shaping machine, of a blank mold comprising a body blank portion and a neck mold portion, a blow mold laterally spaced therefrom, means for disengaging the blank from said body blank portion, transfer mechanism comprising means to embrace the blank while the latter is supported by said neck mold portion, and means to disengage said neck mold portion from the blank, said transfer mechanism being operative to take the bare blank when released from the neck mold portion and transfer it laterally to the blow mold.

2. The combination in a glass-shaping machine, of a blank mold comprising a body blank portion and a neck mold portion, a blow mold, blowing means for the blow mold, means for disengaging the blank from the body blank portion and for subsequently disengaging the blank from the neck mold portion, and means independent of the blank mold portions and of the blowing means for taking the bare blank from the neck mold and transferring it to the blow mold.

3. The combination in a glass-shaping machine, of a blank mold comprising a body blank portion and a neck mold portion, a blow mold laterally spaced from the blank mold, blowing means for the blow mold, means for disengaging the blank from the body blank portion and for subsequently disengaging the blank from the neck mold portion, and means independent of the blank mold portions and of the blowing means for taking the bare blank from the neck mold and transferring it laterally to the blow mold.

4. The combination in a glass-shaping machine, of a blank mold comprising a body blank portion and a neck mold portion, a blow mold, blowing means for the blow mold, means for disengaging the blank from the body blank portion and for subsequently disengaging the blank from the neck mold portion, and means independent of the blank mold portions for engaging the bare blank as it leaves the neck mold and transferring it to the blow mold.

5. The combination in a glass-shaping ma-

chine, of a traveling blank mold having separate portions arranged to be separately opened, and a traveling blow mold at a lower level than the blank mold, the paths of the two molds approaching at one point, transfer mechanism comprising automatic means to embrace an exposed portion of the blank when one of said mold portions has been opened, and which takes the bare blank when the other mold portion is opened and transfers it horizontally and lowers it into the blow mold.

6. The combination with a traveling blank mold having separable body and neck portions and means for opening the body portion and leaving the blank suspended from the neck portion, of a transfer device comprising a reciprocatory arm adapted to engage the blank, means for opening the neck mold at this time and means for moving the arm away with the blank thereon.

7. The combination with a blank shaping machine comprising a blank mold with separable body and neck portions and a blow mold, of a reciprocatory and raising and lowering transfer device independent of the blank mold, adapted to engage the blank, transfer it over the blow mold and lower it therein.

8. The combination in a glass-shaping machine, of two sets of molds traveling in adjacent circular paths and including a set of blank molds each having a body and a neck mold portion arranged to be separately disengaged from the blank therein, and a transfer device separate from the blank molds and brought into blank engaging position when the body portion of the mold has been disengaged, and which takes the blank when disengaged from the neck mold portion and delivers it laterally to the mold of the other set.

9. The combination in a glass-shaping machine, of a traveling blank mold having separable body and neck portions, means for opening the body portion and for opening the neck mold portion, and means for engaging the blank suspended from the neck portion and for transferring the blank therefrom.

10. The combination of a blank shaping machine having a traveling mold, a traveling blowing mold moving in a lower plane, blowing means for the blow mold, and transfer mechanism independent of said traveling mold and of said blowing means for transferring the bare blank from the blank shaping mold laterally over and into the blowing mold.

11. The combination of a blank shaping mold and a blowing mold, means for moving these molds in separate paths, the blank shaping mold traveling on the higher plane, blowing means for the blow mold, and means independent of the blank mold and

of the blowing means at one point in the travel which takes the bare blank from the blank shaping mold and moves it over and lowers it into the blowing mold.

5 12. In a glass-shaping machine, the combination of two relatively rotating carriers, blank molds on one and blow molds on the other, blowing means for the blow molds, and a transfer device on the blow mold carrier to receive the bare blank and transfer it by horizontal and vertical movements to the blow mold, said transfer device operable independently of the parts of the blank mold and of the blowing means.

15 13. In a glass-shaping machine, the combination of two relatively rotating carriers, a blank mold on one and a blow mold on the other, blowing means for the blow mold, a transfer device on the blow mold carrier 20 independent of the parts of the blank mold and of the blowing means for automatically receiving the blank by the disengagement of the latter from the blank mold and transferring it by horizontal and vertical movements into the blow mold and withdrawing therefrom, and a blowing device adapted to engage the blow mold and blow the article.

25 14. In a glass-shaping machine, the combination of a blank forming mechanism and blowing mechanism, each comprising a traveling carrier, and a transfer mechanism on one of the carriers, comprising a rock-shaft 30, a support for the rock-shaft in which it is rocked and raised and lowered, a cam 35 for raising and lowering said rock-shaft, a gear wheel on the rock-shaft, a reciprocating rack bar for rocking said shaft, and a transfer arm carried by the rock-shaft.

30 15. In a glass-shaping machine, the combination of two carriers having thereon blank and blow molds respectively, and a transfer device on the blow mold carrier independent of the parts of the blank mold comprising a forked arm, means for disengaging the blank from all portions of the blank mold, and means for rocking said arm to engage the same with the bare blank as it is disengaged from the blank mold.

45 16. In a glass-shaping machine, the combination of two carriers having thereon blank and blow molds respectively, said blank and blow molds being laterally spaced, and a transfer device on the blow mold carrier comprising a forked arm, and means for actuating said forked arm to cause the same to take the bare blank from the blank mold and transfer it laterally to the blow mold.

50 17. In a glass-shaping machine, the combination of a blank shaping device and a transfer mechanism comprising a traveling carrier, a rock-shaft journaled in the carrier, means for raising and lowering said rock-shaft and for rocking the same, and a transfer arm upon said rock-shaft independent 55 of the blank shaping device adapted to be

moved into and out of the path of the formed blank and adapted to be raised and lowered, for the purpose described.

18. The combination in a glass shaping machine, of a blank mold in which the blank 70 is initially shaped, a blow mold laterally spaced therefrom, means for disengaging the blank from all portions of the blank mold, and means independent of the blank mold engaging the blank after it has been 75 shaped in said blank mold for taking the bare blank from the blank mold and transferring it laterally to the blow mold.

19. The combination in a glass-shaping machine, of a series of blank molds traveling 80 constantly in a circular path, a series of blow molds traveling in a different path located laterally of the first mentioned path, and mechanism arranged to engage the bare blank after it has been shaped in the blank 85 mold and disconnected therefrom and transfer the blank laterally from the blank mold to the blow mold.

20. In a glass-shaping machine, the combination with a series of constantly traveling blank molds and a series of constantly traveling blow molds, of means independent 90 of the blank mold for taking the bare blank from the blank mold and transferring it to the blow mold.

21. In a glass-shaping machine, the combination with a blank shaping mechanism and a blowing mechanism, of means for transferring the blank from one of said mechanisms to the other, including a reciprocal rack-member carried by said blowing mechanism, cammed means for actuating said reciprocal rack-member, a gear wheel carried by said blowing mechanism intermeshing with said rack-member, and a 100 transfer arm attached to said gear wheel adapted to be moved into and out of the path of the formed blank, for the purpose described.

22. The combination with a blank blowing mechanism and blank forming mechanism, of a mechanism for transferring the blank from the blank forming mechanism to the blank blowing mechanism, said blank blowing mechanism comprising a pillar, a 110 table carried by said pillar, and a blank blowing mold upon said table, and said transfer mechanism comprising a slide carried and guided upon the table, a cam-way upon said pillar engaging said slide, a rock-shaft journaled in said table and adapted to be rocked by said slide, a second cam-way 115 upon said pillar, a member upon said rock-shaft and engaging said second cam-way for raising and lowering said rock-shaft, and a 120 transfer arm secured to said rock-shaft and adapted to be moved into and out of the path of the formed blank and out of and into the path of the blank blowing mold.

23. In a glass-shaping machine, the com- 130

- bination with a blank forming mechanism and a blank blowing mechanism, of a transfer mechanism for transferring the blank from the blank forming mechanism to the
- 5 blank blowing mechanism, comprising a slide carried and guided upon said blank blowing mechanism, means for actuating said slide, a gear wheel adapted to be raised and lowered carried upon said blank blowing
- 10 mechanism, means for raising and lowering said gear-wheel, a transfer arm attached to said gear wheel adapted to be moved into and out of the path of the formed blank to engage and transfer the same, and means for
- 15 actuating said gear wheel from said slide.
24. The combination with a blank shaping machine comprising a blank mold with separable body and neck portions and a blow mold, of a reciprocatory and raising and
- 20 lowering transfer device separate from the blank mold, and means to impart to said device vertical and horizontal movements and thereby transfer the blank to the blow mold.
25. The combination of a blank mold comprising a body blank portion and a neck mold portion, a blow mold laterally spaced therefrom, and transfer mechanism comprising means to embrace the blank while
- 30 the latter is supported by said neck mold portion and means to disengage said neck
- mold portion from the blank, said transfer mechanism being operative to take the bare blank when released from the neck mold portion and transfer it laterally to the blow
- 35 mold.
26. The combination of two sets of molds traveling in adjacent circular paths and including a set of blank molds each having a body and a neck mold portion arranged to be separately disengaged from a blank therein, and a transfer device separate from the blank molds and brought into blank-engaging position after the body portion of the mold has been disengaged and which takes a blank when disengaged from the neck mold portion and delivers it laterally to the
- 40 mold of the other set.
27. The combination with a blank mold with separable body and neck portions and a blow mold, of a reciprocatory raising and lowering transfer device separate from the blank mold, and means to impart to said device vertical and horizontal movements and thereby transfer the blank to the blow mold.
